UNITED STATES PATENT OFFICE

121,242

DESIGN FOR A COMBINATION TEMPLE AND ENDPIECE

Thomas E. Bosworth, Cranston, R. I., assignor to
Universal Optical Company, Inc., a corporation
of Rhode Island

Application January 24, 1940, Serial No. 89,684

Term of patent 14 years

To all whom it may concern:

Be it known that I, Thomas E. Bosworth, a citizen of the United States of America, residing at Cranston, county of Providence, State of Rhode Island, have invented a new, original, and ornamental Design for a Combination Temple and Endpiece, of which the following is a specification, reference being had to the accompanying drawing forming a part thereof.

Fig. 1 is a perspective view of a combination temple and endpiece, showing my new design;

Fig. 2 is a top plan of the temple; and

Fig. 3 a side elevation of the temple.

Fig. 4 is a section on line 4—4 of Fig. 3 on an enlarged scale; and

Fig. 5 is a section on line 5—5 of Fig. 3 on an enlarged scale.

The dominant features of my design reside in the single leaf hinge of the temple with forwardly, laterally flaring portions with the upper and lower edges merging into and continuing the line of the endpiece knuckle joint to which the temple is hinged as shown in full lines.

I claim:

The ornamental design for a combination temple and endpiece, substantially as shown and described.

THOMAS E. BOSWORTH.
